FIG. 1

FIG. 2.

Inventor:

R. O'H. P. Theobalds.

by
John A. Scholten
Atty.

UNITED STATES PATENT OFFICE.

REGINALD O'HALLORAN PRINGLE THEOBALDS, OF ST. MARY BOURNE, NEAR
ANDOVER, ENGLAND.

DOMESTIC FIREPLACE.

Application filed December 2, 1925, Serial No. 72,684, and in Great Britain December 4, 1924.

This invention relates to domestic fireplaces, and has for its object to provide an improved construction thereof, particularly adapted for burning coke and anthracite, and 5 equally suitable for burning coal, wood, peat, etc., and tending to the abatement of smoke.

According to the present invention I provide an open fireplace wherein the rear portion of the fuel is supported upon a perforate 10 grate, and the fuel in front for a large proportion of say 25% to 50% of the total fireplace area rests upon a raised plate or support beneath which an air passage is provided opening into the rear portion of the fireplace, 15 the arrangement being such that the front portion of the fire on the raised plate or support heats the air passing through the air passage beneath and entering the fire through the rear portion of the fuel.

20 My invention consists of a fireplace constructed and arranged all as hereinafter more particularly described, and illustrated in the accompanying drawing in which:—

Fig. 1 represents my fireplace in vertical 25 cross section, and

Fig. 2 is a front elevation thereof.

Like characters of reference indicate corresponding parts in the different views.

The imperforate plate *b* which supports 30 the front portion of the fire and the open grate or fire bars *f* which supports the rear portion of the fire are arranged in substantial alignment at a suitable angle.

The open grid or fire bars *f* are fitted so as 35 to slide beneath the imperforate front plate *b* so that the grate may be adjusted to suit requirements.

The front plate 12 in this arrangement extends for substantially 25% of the fireplace 40 area and beneath said plate and the grid or fire bars *f* is arranged a lower plate *b* supported by distance pieces from the imperforate front plate *b*.

The improved construction can be adapted 45 to fit any existing open fireplace, or domestic stove or range, so as to secure a more complete combustion and the reduction of smoke to a minimum.

If desired a complete open fire place, portable or otherwise, or a kitchen range grate 50 may be provided incorporating my invention, or the invention may be applied to furnaces, boilers and the like without necessitating the use of force draught.

Amongst other advantages the present invention introduces features by which a 55 greatly improved combustion is obtained. Frontal draught only is brought to bear at all depths from back to front of the fire. The fire is caused to burn at two levels, and all air drawn in is warmed and dried by the heat 60 from the fire on the higher level situated in front. Also the loss of heat which occurs with the usual fires supported on an open grate, due to the hot dust and ashes automatically falling through the grate is 65 avoided.

What I claim as my invention and desire to 70 secure by Letters Patent is:—

In an open fireplace, the combination with 75 the fireplace side walls and hearth, of a grate including a fuel supporting imperforate front plate raised above the rear portion, said grate extending the width of the fireplace to the side walls thereof and being positioned in spaced relation to the hearth where- 80 by an air supply passage to the rear portion of the grate is constituted by the hearth, fireplace side walls and underneath face of the front portion of the grate, said passage having an unrestricted opening permitting the air entering therethrough to impinge upon the said underneath face of the front portion of the grate.

REGINALD O'HALLORAN PRINGLE THEOBALDS.
